SURGICAL ANASTOMOSIS APPARATUS
AND METHOD

William Edwin Zack, Berwyn, Ill.

Application March 12, 1947, Serial No. 734,032

12 Claims. (Cl. 128—334)

1

This invention relates to surgical devices and more particularly to an anastomosis device useful in surgery for effecting the approximation and healing together of severed arteries, veins or other tubular body parts without the use of suture materials.

An object of the invention is to provide simple, effective structure for such surgical purposes that eliminates the need for the use of suture material and which may be left in place permanently without deleterious effect, being preferably of non-absorbable material, having no tissue reaction or of material that is ultimately absorbable by the body tissues.

Another object of the invention is to provide a surgical device for effecting approximation and healing of severed body organs or parts coupled with the presentation of and maintenance of contact between intima and intima during the healing process and without requiring the use of suture materials.

Still another object of the invention is to provide a novel structure for effecting the foregoing that is simple in construction, simple to use, and that may be manufactured at comparatively low cost.

To the accomplishment of the foregoing and such other objects as may hereinafter appear, the invention consists in the novel construction and arrangement of parts hereinafter to be described and then sought to be defined in the appended claims, reference being had to the accompanying drawings forming a part hereof which show, merely for the purposes of illustrative disclosure, a preferred embodiment of the invention, it being expressly understood, however, that changes may be made in practice within the scope of the claims without digressing from the inventive idea.

In the drawings, in which similar reference characters denote corresponding parts,

Figure 1 is a perspective view of one of the three elements constituting the anastomosis device;

Fig. 2 is a perspective view of a second of the three elements;

Fig. 3 is a perspective view of the third of the three elements;

Fig. 4 is a longitudinal section of the anastomosis device in assembly, and illustrating its application in end to end anastomosis for effecting the approximation intima to intima, and healing of severed vein or artery parts;

Figs. 5—7 inclusive illustrate diagrammatically successive steps in the application of the device to secure the end to end anastomosis assembly shown in Fig. 4;

Figs. 8 to 10 inclusive are diagrammatic views of successive steps utilized in an end to side anastomosis, for example, in the portal vein caval shunt operation for effecting a joint between the vena cava with the portal vein; and

2

Figs. 11, 12 and 13 are views similar to Figs. 1, 2 and 3 of a modification.

Referring to the drawing and first to Figs. 1—3 inclusive, 10 denotes an anastomosis tube. This tube 10 is preferably of material that is non-tissue reactant and non-absorbable. A suitable material of this kind is "Nylon," a commercial product defined as a synthetic fiber forming polymeric amides having protein-like chemical structure derivable from coal, air and water or other substances and characterized by extreme toughness and strength and the ability to be formed into fibers and into various shapes. Other non-tissue reactant materials such as metals known to have such characteristics or synthetic resins or the like that are non-tissue reactant and preferably non-absorbable may be used. It is possible also to use absorbable materials although the non-absorbable are preferable. A suitable absorbable material is formalized gelatin to which polyvinyl alcohol or other suitable slowly absorbable protein material has been added as a plasticizer.

The tube 10 has a flange 11 adjacent one end. The opposite end 12 of the tube has its outer surface reduced in diameter or tapered to provide a bluntly pointed end to facilitate the use of the tube 10 as will be described. The tube 10 is provided with a longitudinally running slot or slit 13. This slot 13 extends from the reduced end 12 toward the flanged end of the tube. The slot 13 functions to permit temporary reduction in tubular dimensions and resilience. A pair of parallelly arranged annular grooves 14, 15 are provided on the outer surface of the tube 10. These grooves preferably have rounded contour as shown in Fig. 4 for purposes presently to be described.

A pair of ring-like clamping members 16, 17 are provided. These rings 16, 17 are of the same material as the anastomosis tube 10. In use, they are adapted to be slipped onto the body of the tube 10 which is rendered yieldable by reason of slot 13, and to rest in and be retained in the respective grooves 14, 15. The internal diameters of these rings are somewhat larger than the least diameters of the respective grooves 14, 15 in which they are retained during use for purposes presently to be described. All sharp edges of the tube 10 and rings 16, 17 are preferably rounded sufficiently to prevent traumatic injury to body parts.

The dimensions of the anastomosis tube 10 and of the clamping rings 16, 17 are dependent upon the particular surgical use to which they are to be put. For example, if surgery of a small vein or artery is contemplated, the dimensions of necessity will be smaller than that of a similar anastomosis tube for use in surgery of larger veins, arteries or of the intestinal tract.

The device described is useful either in end to end anastomosis or in end to side anastomosis. One type of end to end anastomosis is illustrated in Figs. 4 to 7 inclusive. Therein 20 and 21 denote, for example, the severed ends of tubular body organs such as artery parts A, A' which it is desired to reunite. After dissection of the body tissue (not shown) surrounding these severed ends 21, 22, the artery portion A, for example, is drawn through the lumen of the proper size of anastomosis tube 10 from the flanged end (Fig. 5), for example, by appropriate surgical forceps or clamps F, so that the severed end 20 projects forwardly of the end 12 of the tube 10. The severed end 20 is then stretched and folded or drawn reversely over the blunt thinned end 12 of the tube 10 and onto the tube with the aid of the forceps F' to expose the intima I of the artery section A as the outermost surface lying on the tube 10 and with the end 20 lying approximately adjacent the flange 11. The clamping ring 16 is then pushed over this artery-bearing tube 10 until it is felt by a click or snap that the latter overlies the groove 14 which is the one nearest the annular flange 11. Temporary deformation of the tube 10 by reason of slot 13 permits such movement of ring 16 onto the tube 10. The internal diameter of clamping ring 16 is so admeasured that in such position it will retain the artery portion A firmly on the anastomosis tube 10 in the manner in which it has been mounted without causing additional trauma to the artery. Thereafter, the second clamping ring 17 is slid over the other artery portion A' (Fig. 7). The end 21 of this artery portion is then stretched as shown in Fig. 7 by forceps F' to enlarge the lumen of vein portion A' sufficiently to facilitate the insertion into the lumen of the exposed intima I of the artery portion A lying on the tube 10 and already mounted on the latter as described. The extent of insertion is sufficient to bring the end 21 substantially into abutment with the clamping ring 16. Clamping ring 17 is then moved reversely on the artery portion A' towards end 21 until a click or snap indicates alignment with the groove 15 of the tube 10, at which time it functions to clamp the artery portion A' to the artery portion A with the intima I and I' of these two portions in direct contact.

It is seen that, with the anastomosis device of the invention, it is possible to approximate severed vein or artery portions for end to end reunion, to maintain the approximated ends in firm union with intima in contact with intima which is the most desirable condition for healing, and that the necessity for the use of suture materials of any kind is eliminated. Since the material of the device is non-tissue reactant, it may be left permanently in situ without deleterious effects to the patient. If of absorbable material, it ultimately is absorbed by surrounding body tissues. If non-absorbable, it has no deleterious effects because it is made of non-tissue reactant materials.

It is possible also to use the device for end to side anastomosis. For example, in a portal caval shunt operation, junction with a vena cava 29 of a portal vein 30 is required. This is illustrated in Figures 8-10 inclusive. Therein, the severed end 31 of the portal vein 30 is prepared and clamped by a ring 16 to an anastomosis tube 10a in the same way as the severed end 20 of artery portion A was attached to tube 10 with its intima Ia exposed (Fig. 9). A cruciate incision 34 is then

made in the vena cava 29 (Fig. 8). The cut lips 34a of the cruciate incision are then drawn through the second clamping ring 17a as seen in Fig. 9 by the use of forceps Fa and retracted on the opposite side of the ring 17a by these forceps to create an enlarged lumen that is sufficient to facilitate insertion of the prepared portal vein-bearing tube 10a so that the intima Ia on the latter is brought into contact with the intima Ib in the enlarged lumen. Forceps Fb engaging the flange 11a of the tube 10a are used to facilitate the insertion, and forceps Fc are used to facilitate the holding of the vena cava 29 during such insertion. In addition, during insertion, the finger P is placed under the vena cava 29 below clamping ring 17a. When insertion into the stretched lumen Ib is completed, the clamping ring 17a is moved onto the portal vein-bearing tube 10a until the click or snap indicates its positioning over the groove (not shown) corresponding to groove 15. This functions to clamp the intima Ib of the vena cava 29 to the intima Ia of the portal vein 30 and to maintain sufficient pressure without further traumatic injury during healing to accomplish the desired union. Being of non-tissue reactant material, the anastomosis tube 10a and clamping rings 16a, 17a in assembled relationship as described may remain in situ after healing is complete without deleterious effects.

30 End to side anastomosis thus is likewise possible with the device of my invention without alteration in its form.

In the modification of Figs. 11, 12, 13 and 14, 10b donates an anastomosis tube similar to and constructed of the same material as the tube 10 of Fig. 1 except that the end 12b is solid rather than being slotted as in Fig. 1. The tube 10b is provided at one end with a flange 11b and at its opposite end with a rib 14b. For cooperation with the tube 10b there are provided two clamping members 16b and 17b of which 16b is of the same material as the anastomosis tube 10b while the member 17b is of any suitable elastic material permitting expansion of the ring to increase the diameter of its aperture. The member 16b is provided at its inner periphery with a series of small slots 13b. The internal diameters of both clamping members 16b and 17b slightly exceed the external diameter of the portion 12b, but is slightly less than the external diameter of the rib 14b. The slots 13b function to permit temporary increase in the internal diameter of the ring 16b.

In utilizing the modification of Figs. 11 to 13, 55 the clamping members 16b and 17b are applied to the tube 10b in the same manner as previously described, the only difference being that the clamping members are slightly extended during the operation of applying them rather than the tube being slightly reduced. When in place, the clamping members 16b and 17b serve the same purpose as the clamping members 16 and 17 of the embodiment of Figs. 1 to 3 inclusive.

It is to be understood that the particular end to end and end to side anastomosis examples described are illustrative merely. The device is useful in any surgical procedure involving the junction of tubular body parts together or of tubular parts with other body parts and in the performance of artery or vein grafts and the union of the grafted-on artery or vein with other veins or arteries or the like.

While a specific embodiment of the invention has been described, variations in structural detail within the scope of the claims are possible

and are contemplated. There is no intention, therefore, of limitation to the exact details shown and described.

What is claimed is:

1. In a device of the character described, an anastomosis tube having a pair of annular spaced-apart peripheral grooves, a ring-like clamping member movable onto said tube and admeasured to be moved into and retained in one of said grooves, and a second ring-like clamping member movable onto said tube and admeasured to be moved into and retained in the other of said grooves.

2. In a device of the character described, an anastomosis tube having a slot to render it deformable in a portion of its length and a pair of annular parallelly-extending peripheral grooves, a ring-like clamping member movable onto said tube and admeasured to snap into and be retained in one of said grooves, and a second ring-like clamping member movable onto said tube and admeasured to snap into and be retained in the other of said grooves.

3. In a device of the character described, an anastomosis tube of non-tissue reactant material adapted to have body parts mounted thereon and having a flanged end and a bluntly pointed opposite end, and having a slot extending from the bluntly pointed end toward the flanged end to provide resiliency, thereby enabling temporary reduction in tubular dimensions, and said tube having annular spaced-apart peripheral grooves, a clamping ring movable onto said tube from its bluntly pointed end and admeasured to snap into a first of said peripheral grooves and a second clamping ring movable onto said tube from its bluntly pointed end and admeasured to snap into a second of said peripheral grooves, the first of said clamping rings serving to retain a first tubular body part clamped to the outer surface of said tube and the second of said clamping rings serving to maintain a second body part approximated with and clamped to and over a portion of said first named body part carried on said tubular part.

4. In a device of the character described, an anastomosis tube of non-tissue reactant material capable of remaining permanently in situ and adapted to have body parts mounted thereon, said tube having a flanged end and a bluntly pointed opposite end, and having a slot to provide resiliency for temporary deformation in application, said tube also having a pair of annular spaced-apart peripheral grooves, a clamping ring of material like that of said tube movable onto said tube from its bluntly pointed end and admeasured to snap into a first of said peripheral grooves, and a second clamping ring of similar material likewise movable onto said tube and admeasured to snap into a second of said peripheral grooves, the first of said rings serving to retain a first tubular body part on said tube with the intima thereof outermost, and the second of said clamping rings serving to clamp the intima of a second body part into contact with said first named intima.

5. In a device of the character described, an anastomosis tube of non-tissue reactant material capable of being left in situ, said tube having a flanged end and a bluntly pointed opposite end and having a slot to provide resilience for temporary deformation in application, said tube also having a pair of annular spaced-apart peripheral grooves, said tube being adapted to have a tubular body part or organ pass through its lumen from

the flanged end and to receive on its peripheral surface a reversely drawn projection of the tubular body part or organ having its intima lying outermost, a clamping ring of material like that of said tube movable onto the latter from the direction of its bluntly pointed end and admeasured to clamp said reversely folded portion to said tube in the first of said grooves without traumatic injury to the body part, and a second clamping ring of the same material as the first ring adapted to be moved onto said tube from the direction of its bluntly pointed end, said second clamping ring being admeasured to clamp in the second of said grooves intima of another body part or organ into contact with said first named intima without traumatic injury to either body part.

6. In a device of the character described, an anastomosis tube member having a flange at one end and a rib at the remaining end, and a ring-like clamping member movable onto said tube and adapted to snap over and be retained by said rib, one of said members being of variable effective diameter to facilitate assembly.

7. In a device of the character described, an anastomosis tube member having a flange at one end and a rib at the remaining end, and a ring-like clamping member movable onto said tube and adapted to snap over and be retained by said rib, one of said members being slotted to permit variation in its effective diameter to facilitate assembly.

8. In a device of the character described, an anastomosis tube member having a flange at one end and a rib at the remaining end, and a ring-like clamping member moving onto said tube and adapted to snap over and be retained by said rib, said tube member being slotted to permit variation in its effective diameter to facilitate assembly.

9. In a device of the character described, an anastomosis tube member having a flange at one end and a rib at the remaining end, and a ring-like clamping member movable onto said tube and adapted to snap over and be retained by said rib, said ring member being slotted to permit variation in its effective diameter to facilitate assembly.

10. In a device of the character described, an anastomosis tube member having a flange at one end and a rib at the remaining end, and a ring-like clamping member movable onto said tube and adapted to snap over and be retained by said rib, said ring member being of elastic material to permit variation in its effective diameter to facilitate assembly.

11. In a device of the character described, an anastomosis tube member having different diameter portions and a ring-like clamping member movable onto said tube member and adapted to snap into and be retained in the smaller diameter portion of said tube member, one of said members being of variable effective diameter to facilitate assembly.

12. In a device of the character described, an anastomosis tube member having different diameter portions and a ring-like clamping member movable onto said tube member and adapted to snap into and be retained in the smaller diameter portion of said tube member, one of said members being slotted to permit variation in its effective diameter to facilitate assembly.

WILLIAM EDWIN ZACK.
